EMBOSSSED BATHROOM TISSUE SHEET

Lawrence Alfred Walbrun, Menasha, Wis., assignor, to
American Can Company, Greenwich, Conn.

Filed Aug. 22, 1975, Ser. No. 606,781

Term of patent 14 years

Int. Cl. D5—06

U.S. Cl. D59—2 B

FIG. 1

FIG. 2

FIG. 1 is a top plan view of a first, or obverse side of an embossed bathroom tissue sheet embodying my design, and

FIG. 2 is a top plan view of the reverse side of the tissue sheet shown in FIG. 1.

I claim:

The ornamental design for an embossed bathroom tissue sheet, substantially as shown and described.
